(57) **CLAIM**

The ornamental design for a “tubing connector for a grab railing,” as shown and described.

DESCRIPTION

FIG. 1 is a perspective view of the straight tubing connector of the present invention;

FIG. 2 is an end elevational view of the connector of FIG. 1 as seen from each end thereof;

FIG. 3 is a right and left side elevational view of the connector of FIG. 1;

FIG. 4 is a top plan view of the connector of FIG. 1;

FIG. 5 is a bottom plan view of the connector of FIG. 1;

FIG. 6 is a perspective view of a 90° elbow tubing connector of the present invention;

FIG. 7 is a top plan view of the tubing connector of FIG. 6;

FIG. 8 is a side elevational view of the tubing connector of FIG. 6 as seen from the left side thereof;

FIG. 9 is a side elevational view of the connector of FIG. 6 as seen from the right rear side thereof;

FIG. 10 is an end elevational view of the connector as seen from the left side of FIG. 6;

FIG. 11 is a side elevational view of the connector as seen from the right side of FIG. 6;

FIG. 12 is a bottom plan view of the connector shown in FIG. 6;

FIG. 13 is a perspective view of a 45° elbow connector of the present invention;

FIG. 14 is a side elevational view of the connector of FIG. 13 as seen from the right side of FIG. 13;

FIG. 15 is a side elevational view of the connector shown in FIG. 13 as seen from the rear in FIG. 13;

FIG. 16 is a top plan view of the tubing connector of FIG. 13;

FIG. 17 is an end elevational view of the tubing connector of FIG. 13 as seen the right in FIG. 13;

FIG. 18 is a side elevational view of the tubing connector of FIG. 13 as seen from the left side thereof; and,

FIG. 19 is a bottom plan view of the tubing connector of FIG. 13.

The broken lines are for illustrative purposes only and form no part of the claimed design.
